UNITED STATES PATENT OFFICE.

GEORGE HENRY MILLEN, DENIS CASEY, AND JOSEPH HENRY MANTION,
OF HULL, CANADA.

MACHINE FOR FILLING MATCH-RACKS.

SPECIFICATION forming part of Letters Patent No. 449,376, dated March 31, 1891.

Application filed September 25, 1890. Serial No. 366,156. (No model.)

To all whom it may concern:

Be it known that we, GEORGE HENRY MILLEN, DENIS CASEY, and JOSEPH HENRY MANTION, all of the city of Hull, in the Province 5 of Quebec, in the Dominion of Canada, have jointly invented certain new and useful Improvements in Machines for Filling Racks with Match-Splints to be Dipped; and we do hereby declare that the following is a full, 10 clear, and exact description of the same, reference being had to the accompanying drawings, in which—

Figure 1 is a side elevation of our machine. Fig. 2 is a top view of the same. Fig. 3 is a 15 side elevation showing adjusted position of the splint-box while being filled by hand with splints. Fig. 4 is a side elevation showing position of the splint-box and rack-holder with cover open for insertion of an empty 20 rack and removal of a filled one. Fig. 5 is a top view of Fig. 4, showing the match dipping rack in the rack-holder. Fig. 6 is a top view of the machine, the cover of the splint-box open to show the interior perforations. Fig. 25 7 is a vertical section on line *x x*, Fig. 2; and Fig. 8 is a section on line *y y*, Fig. 7, enlarged, to show splints in the box and rack.

Our invention has for its object to rapidly fill or stick match-racks with splints for the 30 purpose of being dipped, so that one end of the splints will be in the same plane notwithstanding any slight difference in the length of the splints, whereby on removal of the filled rack the splints held therein may be 35 uniformly dipped into the igniting compound.

Our invention consists in the construction and combination of certain parts of the machine, as will be hereinafter described, and pointed out in the claims.

1 is a stand supporting the operative parts of the machine.

2 are brackets secured to the top of the stand, in which brackets a shaft 3 is journaled, and to said shaft at the middle is keyed 45 a winding-pulley 4, to which is secured one end of a strap 5, and the other end of the strap is attached to a gravitating weight 6. To near one end of said shaft 3 is secured a winding-pulley 7, to which is secured one end 50 of a strap 8, and near the opposite end of said

shaft 3 is keyed a winding-pulley 9, to which one end of a strap 10 is attached.

11 is a bracket secured to the side of the stand 1, and to said bracket is pivoted a pawl 12, which when required engages a ratchet-wheel 13, keyed on shaft 3, outside the stand 1, and said shaft 3 is provided with a crank-handle 14 for winding pulley 4 against the resistance or gravity of the weight, for the purpose hereinafter set forth, whereby the 60 straps 8 and 10 will be loosened, said straps winding on their respective pulleys in a contrary direction to the strap 5 on pulley 4.

15 is a box to contain the match-splints, said box having arms 16 16 extending from 65 one end, and shaft 3 passes loosely through the outer ends of said arms, whereby said box, pivoted by said arms to the shaft, may be overturned from a horizontal position on one side of the shaft to a horizontal position on the 70 opposite side of the shaft, as shown in dotted lines in Fig. 1, for reversing the box bottom or top uppermost. For overturning or reversing the splint-box by hand, it is provided with 75 handles 18 18.

The top of the splint-box is provided with a hinged door 19, which is securely fastened when closed by a sliding bolt 20, which has inclined-plane notches which engage with the heads of studs 22, secured to one side of the 80 box, or other suitable fastening may be provided to retain the door closed. The bottom of the splint-box has a perforated portion 23 at the end which is lowermost when the splint-box is in an inclined position, as seen in Fig. 85 3. The splints are placed in the splint-box in regular order by hand, the ends against the bottom. The splint-box is held in said inclined position by a prop 27.

The sides of the splint-box are provided 90 with longitudinal slots 24 24, and within the box is a presser bar or follower 25, the ends of which project through the slots 24, and to the ends of the follower are attached the ends of the straps 8 and 10, previously mentioned, 95 so that by gravitation of weight 6 shaft 3 will be rotated and the straps 8 10 wind on the pulleys 7 9, thus drawing the follower toward the perforated portion of the splint-box and maintaining a pressure on the splints to 100

prevent them falling into disorder when standing erect by the box being horizontal. The presser-bar or follower is held stationary against the resistance of the gravitating weight 6, while being filled with splints, by a knob 21 on the follower passing through a hole in the end of the box and held by a hook 26, pivoted to the outside of the box to engage the knob.

10 28 is a wiper-wheel journaled to the end of frame 1, and has contact with a roller 29, journaled to the end of the splint-box and projecting over the wiper-wheel to jolt said box and cause the match-splints therein to fall through the perforations and supply the match-rack with splints in the manner now to be described.

The perforated portion of the splint-box is inclosed by an exterior rack-holder 30, provided with a hinged door 31, which is locked to confine the rack placed in the holder, said locking being effected in the present instance by a bar 32, secured to the door and having a bifurcated projecting end to receive interveningly a locking-bar 33, pivoted at one end to brackets 34, secured to the box, and the other end is pivoted to the eccentric heel of a handle 35, which eccentric portion bears upon bar 32 to keep the door tightly closed. When the handle is thrown back to lie against the splint-box, as seen in Fig. 4, the handle carries with it the locking-bar 33, and door 31 may then be raised or opened to remove the filled rack and replace it by an empty one, the position of the splint-box being then as shown in dotted lines in Fig. 1 and full lines in Fig. 4. After the empty match-rack 36 is inserted in the rack-holder 30, as shown in Fig. 5, and door 31 closed and locked, the splint-box is then 40 endwise overturned or returned to the position shown in Figs. 1 and 2. The ratchet-wheel 13 is then rotated a notch against the resistance or gravity of the weight 6, and pawl 12 engaged with the ratchet-wheel to loosen 45 or remove the tension on the straps 8 and 10, as shown in Fig. 7, and release the pressure of the follower on the splints and thereby diminish the frictional contact of the splints with one another. The wiper-wheel is then 50 rotated to shake or jolt the splint-box and cause some of the splints to fall through the perforations into the corresponding apertures in the match-rack 36, which fits snugly within

its holder 30, which covers the perforated portion of the splint-box. The splints fall 55 through the perforations in the splint-box into perforations in the rack, which has a stationary portion 41 and a movable portion 43, intervened by a wedge 44, to shift said portion to hold the splints in the perforations when 60 the wedge is tightened. The rack may then be removed from the machine and the splints held in the rack dipped into an igniting-compound in any convenient manner.

We claim as our invention—

1. In a match-rack-filling machine, a splint-box 15, hinged at one end to a supporting-frame 1, and having a door 19 and a bottom provided with rows of holes 23, an exterior rack-holder 30, having a door 31 and a presser bar or follower 25 within the splint-box, whereby the splints in the splint-box are transferred through the holes in the bottom to the match-rack when the splint-box is overturned, as set forth. 75

2. The combination, with a supporting-frame having a shaft 3, carrying a pulley 4, winding and unwinding a strap 5, suspending a gravitating weight 6, of the splint-box 15, sleeved at one end on said shaft to turn over 80 the pulley, and having a perforated bottom 23, and exterior rack-holder 30, covering said perforations, a follower 25, extending through slots in the splint-box, straps 8 and 10, attached to the ends of the followers, and pulleys of said shaft winding the straps to automatically maintain a constant tension on the follower, and a pawl and ratchet 12 13, to hold the shaft and loosen the tension of the straps when the shaft is reversed, as set forth, for 85 the purpose described. 90

3. The combination, with the splint-box 15, having an exterior rack-holder and provided with a door 31, having a bifurcated bar 32 extending therefrom, of the locking-bar 33, pivoted at one end to brackets 34 outside said box, and the opposite end hinged to the eccentric end of a handle 35, whereby the eccentric end of the handle presses down and locks the door, as set forth. 95
